(57) **CLAIM**

The ornamental design for a storage and dispensing system for beverage accessories, as shown and described.

DESCRIPTION

FIG. 1 shows a perspective view of a storage and dispensing system for beverage accessories;

FIG. 2 shows a front view of the storage and dispensing system for beverage accessories;

FIG. 3 shows a rear view of the storage and dispensing system for beverage accessories;

FIG. 4 shows a right side view of the storage and dispensing system for beverage accessories;

FIG. 5 shows a left side view of the storage and dispensing system for beverage accessories;

FIG. 6 shows a top plan view of the storage and dispensing system for beverage accessories; and,

FIG. 7 shows a bottom plan view of the storage and dispensing system for beverage accessories.

The shade lines in the Figures show contour and not surface ornamentation.

The broken lines shown in the Figures show portions of the storage and dispensing system for beverage accessories which form no part of the claimed design.
